UNITED STATES PATENT OFFICE

ETTA MOTTERAM, OF CLAPHAM, LONDON, ENGLAND

MEDICAL PESSARY

Application filed May 10, 1928, Serial No. 276,725, and in Great Britain May 16, 1927.

This invention relates to medical pessaries for the relief and cure of leucorrhea and other inflammatory conditions of the vagina, uterus, fallopian tubes and ovaries, and other similar ailments.

In the improved pessary constructed in accordance with the present invention, the lotion is contained in a soluble gelatine or other similar core of conical or ovoid form 10 which is carried within a container of sponge or similar material which extends up to near the top of the gelatine core.

In the preferred form of pessary constructed in accordance with the invention the 15 lotion-containing core resembles an acorn and the container the cup except that the container extends beyond the height to which the cup of the acorn normally reaches. The top surface of the container may either be

20 plane or undulating.

Suitable means such as a ribbon or the like are preferably secured to the container to facilitate withdrawal of the pessary.

Referring now to the accompanying drawing which illustrates a preferred form of medical pessary formed in accordance with the present invention, a lotion-containing core *a* of soluble glycerine or similar material is housed within a container *b* of sponge or similar absorbent material which fits over the core but does not extend to the top thereof.

In order to facilitate withdrawal, a ribbon *c* is preferably attached to the container and is provided at its free end with a bone, rubber or other suitable ring *d*.

I claim:

1. A medical pessary comprising in combination a lotion-containing soluble core and an absorbent container which encloses the 40 lower portion of the core.
2. A medical pessary comprising in combination a lotion-containing soluble core and an absorbent container which encloses the core up to near the top thereof.
- 45 3. A medical pessary comprising in combination a lotion-containing soluble core of ovoid form and an absorbent container which encloses the lower portion of the core.
4. A medical pessary comprising in combination a lotion-containing soluble core and

a sponge container which encloses the lower portion of the container and allows the top portion of said container to project.

5. A medical pessary comprising in combination a lotion-containing soluble core of 55 ovoid form and a sponge container which encloses the lower portion of the core.

6. A medical pessary comprising in combination a lotion-containing soluble core, an absorbent container which encloses the lower 60 portion of the core and a withdrawal ribbon secured to the container.

7. A medical pessary comprising in combination a lotion-containing soluble core, a sponge container, a ribbon secured to the 65 container and a ring secured to the free end of the ribbon.

In testimony whereof I affix my signature.

ETTA MOTTERAM.
